UNITED STATES PATENT OFFICE.

ALBERT F. WELLE, OF ST. LOUIS, MISSOURI, ASSIGNOR TO AMERICAN BAKERY COMPANY, OF ST. LOUIS, MISSOURI.

DESIGN FOR A SHEET OF WRAPPING PAPER.

Application filed March 9, 1923. Serial No. 5,425. Term of patent $3\frac{1}{2}$ years.

To all whom it may concern:

I, ALBERT F. WELLE, a citizen of the United States, residing in the city of St. Louis and State of Missouri, have invented a new, original, and ornamental Design for a Sheet of Wrapping Paper, of which the following is a specification, reference being had to the accompanying drawing, forming a part thereof.

The figure is a plan view of a sheet of wrapping paper showing my design.

I claim:

The design for a sheet of wrapping paper substantially as shown.

ALBERT F. WELLE.
